Daryl G. Schreder
ATTORNEY

UNITED STATES PATENT OFFICE.

EARL W. STORMS, OF OAKLAND, CALIFORNIA.

WINDOW FRAME.

Application filed August 17, 1927. Serial No. 213,516.

My invention relates to window frames, and it refers especially to an improvement in window frames of the type described in my application for Letters Patent of the United States, filed March 21, 1927, Serial Number 177,001.

In the aforementioned application I disclosed, together with other forms of construction, a window frame, which comprises upper and lower substantially horizontal members and has wedges secured transversely to the lower horizontal member so as to be spaced from the ends thereof, and also substantially vertical members positioned directly above the respective wedges and joining the upper horizontal member to the sill in order to support it rigidly thereon.

While this construction of the window frame is cheap, and while it satisfactorily meets all ordinary requirements for window frames, it is defective in the respect that it leaves the intermediate portion of the window sill unsupported and allows that portion to sag, so that in time the window sash will not fit the sill and thus the window-frame opening cannot be effectively closed.

The main object of my present invention is to provide a window frame, in which the sill is supported upon a unitary wedge element so that the sill can not sag at any portion thereof.

Other objects and advantages will be understood from the following detailed description, illustrated in the accompanying drawings, in which:

Figure 1 is an elevation of a preferred form of window frame, constructed according to my invention and set in a wall frame,

Figure 2 is a section of the window frame taken in a plane indicated by the line 2—2 in Figure 1,

Figure 3 is an elevation of the lower portion of a window frame, different from that shown in Figure 1, but constructed according to my invention, a portion of the wall frame, in which the window frame is set, being indicated in dotted lines,

Figure 4 is an elevation of still another embodiment of my invention, especially adapted for casement window-frame construction, a portion of the wall frame, in which the window frame is set, being indicated by dotted lines,

Figure 5 is a sectional detail of the relative position of a reversible casing and an interchangeable jamb or pulley stile, and

Figure 6 is a sectional detail of another adaptation of the interchangeable jamb or pulley stile.

In the form of my invention, illustrated in Figures 1 and 2, the window frame 1 is set in an opening formed in a wall frame, the studs 2 thereof are equally spaced and are cut away so as to include an opening 1^a substantially longer than the window frame. 60 This window frame comprises substantially horizontal head-jamb 3, a unitary wedge 4, a sill 5 extends longitudinally of the wedge and is secured to the upper side thereof, so that, when the frame 1 is set in the wall-frame 65 opening, the sill slopes outward and downward, as shown in Figure 2. At a suitable distance from its respective ends the head-jamb 3 is on its underside preferably provided with transverse grooves, in which are 70 respectively fixed the upper ends of substantially vertical jambs or pulley stiles 6 having their lower ends fixed in corresponding grooves formed in the upper side of the sill, and the head-jamb and the sill are preferably 75 recessed at their ends and have fixed in the recessed portions the respective ends of substantially vertical supporting members 7, the outer side faces of which are flush with the 80 respective ends of the head-jamb and the sill, so that window frame is thereby adapted to be nailed to the studding of the wall frame and to form a support within the latter. The horizontal cross members 7^a are disposed on the studding adjacent to the head-jamb and 85 the unitary wedge as shown in Figure 1. The aforescribed window frame may be shifted longitudinally in the opening 1^a to any desired position. When the opening snugly 90 fits the frame then the lower horizontal member 7^a may be eliminated.

If the frame 1 is to be used in connection with the sliding sashes the jambs or pulley stiles are preferably rabbeted so as to receive respective bead strips 8 therein between 100 the sashes, and the head jamb 3 is similarly rabbeted for the reception of a horizontal bead strip 9. When sliding sashes are used, the jambs or pulley stiles, of course, are provided with openings for receiving the sash-balancing devices therein, such devices, in connection with the window frame, being indicated by dotted lines, as placed in the pockets that are respectively formed at both 105 sides of the window frame between the jambs or pulley stiles 6 and the supporting members 7. After the placing of the sashes, not 110

shown, in their respective positions in the window frame, the usual horizontal and vertical casings or stops are secured to the frame for retaining the sashes therein, only portions 5 of the vertical casing or stops 10 in this instance being shown in Figure 2. When a window frame, thus constructed, has been secured in its proper position in the wall frame, the wall is sheathed and plastered, and the 10 window casing is fitted, so that the manner in which the window frame is jointed to the wall frame is thereby made inconspicuous.

The lower portion of another type of a window frame 11, which at its upper portion 15 is similar to the frame 1, already described, is shown in Figure 3. In this instance, a lower horizontal member 12 is in its upper side provided with transverse grooves, formed in correspondence with the grooves 20 formed in the underside of the head-jamb 3 shown in Figure 1, and in the grooved portions of the lower horizontal member are respectively fixed the lower ends of the jambs or pulley stiles 13. Preferably, the horizontal 25 member 12 is at its ends also recessed in correspondence with the recessed ends of the head-jamb, and the respective lower ends of the supporting member 14 are fixed in the recessed portions of the lower horizontal 30 member. The frame 11 further differs from the frame 1 in that the wedge 15, while it is secured longitudinally upon the lower horizontal member 12, extends only between the jambs or pulley stiles 13, which may have 35 therein obliquely transverse grooves for receiving the transverse edges 16 of respective recessed portions of the sill 17, so that, when the window frame 11 is set in a wall frame, as is suggested by the dotted lines in Figure 40 3, the sill slopes outward and downward and with the respective longitudinal edges 18 of the recessed portions extends in front of the window frame. While in this construction, by the setting of the sill in the 45 oblique grooves, leaking of water at the sill into the frame 11 is prevented, and while the oblique grooves support the sill at the recessed portions, it is evident that the sill is also supported upon the wedge and thereby 50 effectively prevented from sagging at any portion thereof.

In Figure 4 are shown portions of a window frame 19, which is particularly adapted to be used as a casement window-frame, or door-frame, although it also may be used as a frame for sliding sashes. Like the frame 1, shown in Figure 1, the frame 19 is provided with a head-jamb 20, a lower horizontal member 21, a wedge 22 secured longitudinally 55 upon the wedge. The frame 19, however, differs from the frame 1 in that it has only a pair of jambs or pulley stiles 24, which with their lower ends are fixed in transverse grooves at a distance from the respective ends 60 of the sill and, with their upper ends, are

fixed in transverse grooves correspondingly spaced from the respective ends of the head jamb. In this instance, the jambs or pulley stiles 24 take the place of the jambs 6 in the frame 1 and are made comparatively heavy 70 in order to be capable of efficiently supporting thereon not only the head jamb but also that part of the wall structure which rests upon the head jamb. It should be noted in this connection that, by the extension of the 75 head-jamb 20 beyond the jambs or pulley stile 24, some of the weight of the superstructure is placed upon the ends of the horizontal member and thereby counteracts any tendency of the horizontal member to sag at its 80 center. It should also be observed that, when the window frame 19 is set in a wall frame, indicated by dotted lines, the pockets 25—are formed by the respective jambs, the respective wall-frame studdings at the sides of the 85 window frame, and the respective ends of the upper horizontal member and the sill—are adapted to receive therein suitable sash-balancing devices whenever it is required to use the frame 19 in connection with sliding 90 sashes. The extension of the members 20 and 23 may be used for securing the apron or stool or casing thereto, also for keylocking the frame to a brickwall or concrete structure.

From the foregoing it is obvious that in 95 the different forms of my present invention the unitary wedge elements effectively prevent the sagging of the sills at any portions thereof and thereby also serve as means for preventing such disarrangement or warping 100 of the vertical members or other parts of the frames as may result from the sagging and is liable to cause binding of the sashes in the frames. It is further evident that the window frames of my invention are strong and 105 durable and that they may be made cheaply and accurately to order in large quantities so that they may be set quickly and efficiently in suitable wall-frame openings even by unskilled workmen.

In order to further facilitate the setting of 110 my window frame I provide a special type of interchangeable jamb or pulley stile 26 and a reversible and interchangeable casing 27. It is a common trouble at present that the 115 workman must be very careful about choosing the right hand or left hand jamb or pulley stile before setting the window frame. The jamb 26 shown in Figure 5 is provided with grooves 28 at the opposite sides thereof 120 so that the parting bead 29 may be attached thereto regardless which side of the jamb is turned toward the window opening. Thus right hand and left hand jambs are interchangeable. Securing groove 30 is provided 125 for receiving a ground 31 shown in Figure 6. A keylock 32 shown in dotted line is used when the wall is rounded down to the jamb. Another novel feature of the jamb 26 is that a corner 33 is cut in and squared to present 130

another bearing surface 34. Ordinarily 2 x 3 or 2 x 4 supports are used adjacent to the jamb. When 2 x 3 support is used the lath and plaster wall is on the surface 34 permitting the use of any casing over the jamb to be secured in the securing groove 30. When 2 x 4 support is used then the same jamb 26 may be employed the only difference being that the lath and plaster wall is resting upon the outer surface of the jamb 26. In the event an inside casing is used it is secured on the ground 31. A stop 35 is used to guide the window sash in case of sliding windows.

The casing 27 is made reversible by means 15 of the grooves 36, so that both sides and both ends of the casing are adapted to receive a mold. The casing as shown in Figure 5, and in Figure 6 may be used as an outside or inside casing or on the left and on the right 20 hand jamb. The grooves also serve to engage a male protrusion 37 of the jamb 26.

It is evident the jamb and casing heretofore described make the window frame readily adaptable to any kind of wall finishing 25 such as stock, plaster, masonry or rustic mold.

I claim as my invention:

1. A window frame adapted to be set in, and to support, a wall structure, the frame comprising an upper horizontal member; a 30 sill, extending substantially parallel with said member, and being spaced therefrom; substantially vertical members joined to the sill and to the upper horizontal member; and a unitary wedge element mounted in the frame so as to prevent sagging of the sill at any portion thereof.

2. A window frame adapted to be set in, and to support, a wall structure, the frame comprising an upper horizontal member; a 40 sill extending longitudinally in spaced relation to said horizontal member; substantially vertical members joined to the sill and to the upper horizontal member; and a unitary wedge mounted on the underside of the sill 45 so as to prevent sagging of the latter at any portion thereof.

3. A window frame adapted to be set in, and to support, a wall structure, the frame comprising upper and lower substantially 50 horizontal members; substantially vertical members, and a sill supported upon the lower horizontal member, the vertical members supporting the upper horizontal member and being joined to the sill, horizontal members extending beyond vertical members forming pockets, as, and for the purpose, set forth.

4. A window frame adapted to be set in, and to support, a wall structure, the frame comprising upper and lower horizontal members; inner and outer substantially vertical members joining the upper and lower horizontal members to each other so as to support the upper horizontal member upon the lower horizontal member, the inner vertical members having openings therein for the recep-

tion of sash-balancing devices; and a sill joined to the inner vertical members so as to slope outward and downward when the frame is set in the wall structure.

5. The combination with the wall of a 70 building having an opening therein of a window frame being of such a size that the position thereof is longitudinally adjustable in the opening, said window frame comprising a sill, a head-jamb disposed opposite said sill, vertical jambs joined to the sill and to the head-jamb so as to support the wall structure, and a unitary wedge element mounted on the sill to prevent sagging of the sill at any portion thereof.

6. A window frame adapted to be set in and to support a wall structure, the frame comprising a head-jamb, a sill disposed in spaced relation to said head-jamb, interchangeable vertical jambs joined to the sill 85 and to the head-jamb.

7. A window frame adapted to be set in and to support a wall structure, the frame comprising a head-jamb, a sill disposed in spaced relation to said head-jamb, interchangeable vertical jambs joined to the sill and to the head-jamb, and a unitary element supporting the sill so as to prevent sagging of the sill at any portion thereof.

8. A window frame adapted to be set in and to support a wall structure, the frame comprising a head-jamb, a sill disposed in spaced relation to said head-jamb, interchangeable vertical jambs joined to the sill and to the head-jamb, and a wedge secured longitudinally to the downward sloping sill so as to reinforce said sill and to prevent the sagging of the sill at any portion thereof.

9. In combination a window sill, a head-jamb, vertical jambs to be joined to the sill and to the head-jamb, and means for parting said window frame; said jambs to have grooves disposed on the opposite faces thereof for receiving said parting means, thereby to render said jambs interchangeable.

10. In combination a window sill, a head-jamb, vertical jambs to be joined to the sill and to the head-jamb, and means for parting said window frame; said jambs to have grooves disposed on the opposite faces thereof for receiving said parting means, thereby to render said jambs interchangeable, said jambs to have a plurality of bearing surfaces for the wall, said surfaces to be disposed in steps so as to permit the use of said jambs in connection with different size studdings.

11. The combination with the walls of a building having wall covering thereon of a window sill, a head-jamb, vertical jambs to be joined to the sill and the head-jamb, and casings to be secured to said jambs, said casings to have grooves therein for receiving the ends of said wall covering, said grooves to be so disposed on said casings as to render said casings reversible and interchangeable.

12. The combination with the walls of a building having wall covering thereon of a window sill, a head-jamb, vertical jambs to be joined to the sill and the head-jamb, and a casing to be secured to said jambs, said casings to have grooves therein for receiving the ends of said wall covering, said grooves to be so disposed on said casings as to render said casings reversible and interchangeable, and a tongue on the side of each jamb to engage 10 one of said grooves on said casings.

In testimony whereof I affix my signature.

EARL W. STORMS.
